United States Patent Office.

JOHN TROXEL, OF REEDSBURG, OHIO.

Letters Patent No. 69,512, dated October 1, 1867.

IMPROVED MOP-HEAD.

The Schedule referred to in these Letters Patent and making part of the same.

TO ALL WHOM IT MAY CONCERN:

Be it known that I, JOHN TROXEL, of Reedsburg, in the county of Wayne, and in the State of Ohio, have invented certain new and useful Improvements in Mop-Heads; and do hereby declare that the following is a full, clear, and exact description thereof, reference being had to the accompanying drawings, and to the letters of reference marked thereon.

In the annexed drawings, making part of this specification, A A represent two jaws, which may be provided (one or both) with teeth for holding a mop-rag between them. The arms B B of these jaws cross each other, and are pivoted together, as seen at x. The outer ends of these arms are pivoted to the ends of two levers D and C, said levers being crossed and pivoted together. By this arrangement compound leverage is obtained. One of the levers C is serrated or notched upon its outer end, and a link, E, upon lever D, catches over this notched end, when desirable, for holding the two levers together, and consequently the two jaws A A, for the jaws open and close with the levers. When the mop is placed between the jaws A A, and the levers D and C are brought together and confined by the link E, it is held securely while being used, but can readily be detached by separating the levers, so that it can be washed and wrung out.

What I claim as new, and desire to secure by Letters Patent, is—

The arrangement of the heads A A, arms B B, levers C and D, and link E, the several parts being constructed and operating in the manner and for the purpose set forth.

In testimony that I claim the foregoing I have hereunto set my hand this 30th day of July, 1867.

JOHN TROXEL.
